(57) **CLAIM**

The ornamental design for a mounting adapter, substantially as shown and described.

DESCRIPTION

FIG. 1 is a perspective view of a mounting adapter according to the design.

FIG. 2 is a right-side elevation view of the mounting adapter shown in FIG. 1.

FIG. 3 is a left-side elevation view of the mounting adapter shown in FIG. 1.

FIG. 4 is front-side elevation view of the mounting adapter shown in FIG. 1.

FIG. 5 is rear-side elevation view of the mounting adapter shown in FIG. 1.

FIG. 6 is a top plan view of the mounting adapter shown in FIG. 1; and,

FIG. 7 is a bottom plan view of the mounting adapter shown in FIG. 1.

The broken line showing of a mounting adapter is for the purpose of illustrating portions of the article and forms no part of the claimed design.
